CRANK CASE COOLER

William Grickscheit, Detroit, Mich., assignor of
one-third to Jesse W. Shough and one-third to
Kenneth T. Freeman, both of Detroit, Mich.

Application October 23, 1933, Serial No. 694,897

2 Claims. (Cl. 123—171)

The invention relates to cooling means designed for use in connection with internal combustion engines with the primary purpose of cooling the lubricating oil and the invention 5 consists in the novel construction as hereinafter set forth.

In the drawings:

Fig. 1 is a side elevation partly in longitudinal section through an internal combustion engine 10 to which my improvements are applied;

Fig. 2 is a sectional plan view thereof;

Fig. 3 is a cross section;

Fig. 4 is a sectional plan view, and

Fig. 5 is a cross section through a modified 15 construction.

In the operation of internal combustion engines it is well understood that the lubricating oil if highly heated loses to a considerable extent its lubricating properties. It is usual to hold the 20 oil supply in the oil pan or sump formed in the lower portion of the crank case and consequently the heat of the crank case is communicated thereto. I have therefore devised a system of cooling which is applied not only to the direct 25 cooling of the oil but also to the lessening of the heat communicated to the crank case from the engine cylinders. As illustrated, A is a multi-cylinder internal combustion engine for use on a motor vehicle, B are the individual cylinders 30 thereof; C the pistons; D the crank case; E the crank shaft and F the rods connecting the pistons to the cranks. The lower portion of the crank case forms an oil reservoir from which the oil is distributed to the parts to be lubricated 35 by any suitable system (not shown).

To cool the oil and the crank case, I have devised the following construction: G is an air conduit, preferably having a bell shaped mouth G' so located as to receive a blast of cool air 40 due to the forward movement of the vehicle. H is a filter in the conduit G for removing dust or grit from the air current and I is a throttle valve for variably restricting the quantity of air permitted to pass. The conduit G enters the 45 crank case D through one end thereof near the bottom and extends longitudinally through the case as indicated at J in a position where it will be immersed in the oil. Connected with this portion J at various points are conduits K of 50 smaller dimension which extend vertically upward in the crank case and to a point which will be within the hollow piston C when the latter is at the lower end of its stroke. The end of the portion J of the conduit is contracted as 55 indicated at L and is then turned upward to

extend above the oil, as shown at M. O is a breather or air outlet which is connected to the crank case.

With the construction as thus far described, when the engine has been running for a sufficient length of time to become thoroughly heated, the throttle I is opened by suitable means such as a rod N extending to a point accessible to the driver. This will permit cold air to enter the bell mouth G', pass through the filter and by 10 the throttle valve into the portions J of the conduit which are immersed in the oil. Also air is discharged through the conduits K into the upper portion of the crank case and into the hollow pistons each time they are at the downward end of the stroke. Also, when the pistons are at the upper end of the stroke, air discharged from the conduits K will contact with a portion of the wall of the cylinder. The air discharged from these conduits and also that 15 discharged from the restricted end conduit M will pass out of the crank case through the breather or outlet O, thereby dissipating a large portion of the heat which usually is imparted to the oil. Furthermore, as the temperature in the 20 cylinders and upper portion of the crank case is much higher than the temperature of the oil, it is obvious that after heat has been extracted from the oil by the air in the conduit J, this air is still at a lower temperature than the 25 upper portion of the crank case and is capable of extracting further heat. Thus I obtain the greatest efficiency in cooling the oil by using the air first to directly extract heat from the oil and subsequently to extract further heat from the 30 source which would otherwise be communicated to the oil.

For certain uses it may not be necessary to have this double cooling effect, but only to extract the heat directly from the oil. This is illustrated in the modified construction, Figs. 4 and 40 5, in which P is a bell shaped air conduit having a cover plate or throttle Q directly hinged thereto and under the control of the driver. The conduit P enters the crank case through the end 45 wall thereof and then connected to a transverse header R which in turn is connected to a series of conduits S passing longitudinally through the oil pan, being connected at their rear ends with a header T while the latter is connected to a conduit U passing through the rear wall of the crank case. With this construction the air which is admitted through the conduit P is distributed through all of the conduits S which being 50 immersed in the oil, will extract the heat directly 55

therefrom. In both of the constructions described the cooling may be controlled by the operator so that in cold weather the quantity of air may be restricted or cut off altogether.

5 5 What I claim as my invention is:

1. The combination with a motor vehicle internal combustion engine having a crank case with an oil reservoir in the lower portion thereof, and a plurality of cylinders connected with the crank case, of a cooler comprising a conduit having its entrance end located to receive air due to the forward movement of the vehicle, said conduit having a portion extending through said crank case and immersed in the oil therein, a 10 plurality of conduits of smaller capacity connecting with the conduit immersed in the oil and extending upward into the several cylinders, a restricted outlet for the end of said first mentioned conduit also extending upward in the 15 crank case and a breather or outlet for the air discharged from all of said conduits.

2. The combination with a motor vehicle internal combustion engine having a crank case with an oil reservoir in the lower portion thereof and a plurality of cylinders connected with the crank case, of a conduit having a bell shaped mouth located to receive air due to the forward movement of the vehicle, said conduit having portions entering the end of the crank case and extending through the same below the level of the oil, the inner end of said conduit being restricted and extending upward in the crank case, a plurality of smaller conduits connecting to the portion of the conduit passing through the oil and discharging at points within the respective cylinders and so as to be directed against the 15 pistons therein, a breather or outlet for the air discharged from said conduit and a filter in the inlet end of said conduit for extracting dust and grit from the air. 10
